(57) **CLAIM**

The ornamental design for advertisement display device, as shown and described.

DESCRIPTION

FIG. 1 is a perspective interior view illustrating my design for an advertisement display device;

FIG. 2 is a perspective exterior view thereof;

FIG. 3 is a top perspective view thereof;

FIG. 4 is a front elevational view thereof;

FIG. 5 is a top view thereof;

FIG. 6 is an enlarged end view thereof, the opposite end view being a mirror image thereof;

FIG. 7 is a bottom view thereof; and,

FIG. 8 is a perspective view in exploded form of the components of FIGS. 1 and 2 thereof.

In the drawings, the broken lines represent features that form no part of the claimed design.
